UNITED STATES PATENT OFFICE.

JOSEPH A. ANGLADA, OF PHILADELPHIA, PENNSYLVANIA, ASSIGNOR TO BAKER WHEEL & RIM COMPANY, OF CHICAGO, ILLINOIS, A CORPORATION OF ILLINOIS.

METHOD OF PRODUCING WHEELS.

1,236,323.

Specification of Letters Patent.

Patented Apr. 6, 1920.

Application filed May 17, 1918. Serial No. 235,115.

To all whom it may concern:

Be it known that I, JOSEPH A. ANGLADA, a citizen of the United States, and a resident of Philadelphia, county of Philadelphia, and State of Pennsylvania, have invented certain new and useful Improvements in Methods of Producing Wheels, of which the following is a specification.

My invention relates generally to improvements in metallic wheels, and especially methods of producing same, and is concerned primarily with motor vehicle wheels.

The general object of my invention is to provide a metallic vehicle wheel which shall be light in weight yet strong, resilient, and durable and better adapted to withstand service conditions than wheels of similar size and weight heretofore devised.

A further object of my invention is to provide a method of producing a metallic vehicle wheel from sheet metal, in a simple, expeditious manner at low cost;—and a particular object is to provide a method of producing metallic vehicle wheels from sheet metal, substantially without waste of material.

My invention consists generally in a method of producing such wheels, whereby the above named objects together with others which will appear hereinafter are attainable.

My invention also consists in the details of construction and combination of parts hereinafter described and particularly pointed out in the claims.

My invention will be more readily understood by reference to the accompanying drawings, which illustrate wheels embodying my invention and methods for producing same and which I consider the best at the present time.

In said drawings, Figure 1 depicts a portion of sheet metal stock from which the wheel is formed;—Fig. 2 illustrates one of the steps in the production of the wheel;—Fig. 3 illustrates a blank or element resulting from the operation depicted in Fig. 2;—Fig. 4 illustrates the blank of Fig. 3 formed to constitute a part of the wheel;—Fig. 5 is a cross-sectional view of the felly band which I use in manufacturing the wheel;—Fig. 6 is a sectional view illustrating the assembled wheel blank and felly band;—Fig. 7 is a face-view of the com-

pleted wheel;—Fig. 8 depicts a blank or member similar to Fig. 3, but with the spoke portions staggered;—Fig. 9 is a cross-sectional assembly illustrating the blank of Fig. 8, shaped and combined with the felly band;—and, Fig. 10 is a face-view of the completed wheel of the form shown in Fig. 9.

I am aware that it has been proposed heretofore to manufacture metallic vehicle wheels from sheet metal, but in the methods heretofore prevailing great wastage of material has resulted, due very largely to the methods of manufacture which usually consisted in stamping or pressing the complete circular wheel out of a square sheet of metal larger than the projected area of the plane of the wheel. The wastage resulted not only from the manufacture of a circular wheel, from a square sheet of metal, but also in those types having spokes, from the removal of considerable portions of metal between adjacent spokes. It is one of the objects of my invention to eliminate very largely this expensive wastage of material and to provide a method whereby a metallic vehicle wheel can be produced from commercial sheet metal such, for example, as hot or cold rolled steel, in a rapid and inexpensive manner.

In practising my invention, I prefer instead of using a square sheet of metal to start with a sheet of elongated shape, the length of which will be substantially equal to the circumference of the hub of the wheel desired and of such width as to enable the production, simultaneously, of a plurality of blanks or members of a character suitable for producing the major portion of the wheel. In the present instance I manufacture a plurality of blanks from a single sheet of metal with the spoke portions of the wheel blanks so relatively positioned as to interfit and to permit cutting from the sheet substantially without wastage.

Having now set up the general method of procedure, I shall describe my invention in detail with reference to the accompanying drawings. In said drawings, 2 represents a portion of a sheet of metal which may be of any convenient size and from which a plurality of wheel blanks or elements can be produced; the thickness of the metal is such as is suitable for the particular type of wheel being manufactured and the character

of the metal will be determined very largely by the service conditions to be imposed upon the wheel, for example, if the wheel is for use on a large, heavy vehicle, the sheet metal 5 will be thicker than for wheels used on the lighter type of passenger vehicles, where resiliency is of more importance than great strength. The sheet metal, 2, in this instance is next sheared or severed longitudinally, along the dotted lines, 7 and 8 (see Fig. 2), thus producing simultaneously a number of wheel blanks or elements, one of which is shown in Fig. 3, and designated by the numeral 9. The blank or element, 9, 10 comprises a central portion, 10, and spaced tongue like projecting portions, 11.

As will be seen shortly, the portion 10, constitutes the hub of the wheel and the portions, 11, constitute the spokes of the wheel 20 and for this reason I shall refer hereinafter to the portion, 10, as the hub portion, and to portions, 11 as the spoke portions. The length of the hub portion, 10, is equal substantially to that of the circumference of the 25 hub desired in the finished wheel, and the blank or element shown in Fig. 3 is rolled or shaped so that the hub portion constitutes a cylinder. The end portions 12 and 13 of the thus cylindrically shaped hub portions 30 will be in end to end abutment and I prefer to join them permanently as by means of welding. The spoke portions, 11, are bent upwardly or away from the central cylindrical hub portion and in the instant case 35 are brought quite close together, providing a small intervening space, 14, between adjacent spokes (see Fig. 4) of such size as to accommodate the flange portion, 16, of a felly band, 17 (see Figs. 5 and 6). The felly 40 band, 17, is of standard construction, designed to receive a demountable rim having for this purpose a co-acting conical side flange, 18. It will, of course, be understood that a felly band of other or desired form 45 may be used. The felly band is positioned, as shown in Fig. 6, and the spoke portions, 11, are rigidly secured thereto by means of rivets, 19. While the spoke portions, 11, are shown as abutting the flange, 16, upon the 50 side nearest to the end portion of the hub from which the spoke projects the spokes may, if desired, be secured upon the opposite or far-side of the flange, and such construction will be shown and described shortly, 55 with a slightly modified form of wheel embodying my invention. The completed wheel is well shown in Fig. 7 and it is thought that no further detailed description thereof is necessary. By producing a wheel 60 under the method described, there is practically no waste stock, inasmuch as the spoke portions of adjacent wheel blanks interfit.

In that form of my invention thus far described, spoke portions radiating from opposite ends of the hub are in alinement, so that

viewing the wheel in side elevation, as shown in Fig. 7, but half of the actual number of the spokes in the wheel are seen. In this form the felly band is supported at only a relatively few spaced points. For some purposes it may be desirable to stagger the spokes, *i. e.*, to alternately distribute the spokes radially from the opposite ends of the hub portions equally throughout the circumference of the wheel, thus securing in 75 appearance a wheel more nearly resembling a wire wheel, and also distributing the points of support more uniformly throughout the circumference of the felly band. I have disclosed such a wheel and a method 80 for producing same in Figs. 8, 9 and 10 of the drawings, wherein 30 represents the hub portion of a wheel blank; 31 the spoke portions, projecting from one side thereof; and 32, the spoke portions, projecting from the 85 opposite side. The respective spoke portions, 31 and 32, are staggered, as shown, so that instead of an outer spoke being directly opposite an inner spoke, as shown in Fig. 3, they are here staggered. To enable cutting 90 a plurality of blanks from a single sheet without wastage, I also bevel or angle the end portions 33 and 34 of the hub. The wheel blank thus described is formed so that the hub constitutes a cylinder;—end portions, 33 and 34, being welded or otherwise 95 permanently joined and the spoke portions, 31 and 32, being bent upwardly or away from the hub to form radiating spokes, as shown in Figs. 9 and 10. In this instance, 100 the spoke portions are bent so that the ends, 31' and 32', are on opposite sides of the center line. A felly, 17, of the same construction described with reference to the first form of the invention is secured in place as 105 by riveting or in any other suitable manner. The completed wheel is well shown in Fig. 10, wherein the staggered relation of the spokes and the multiple point supports are well shown.

The difference in appearance and construction of the two types of wheels can be contrasted by viewing Figs. 7 and 10.

It will be understood that these wheels are initially and permanently tensioned. 115 This I accomplish in the act of welding or riveting the ends of the spokes to the radial flange of the felly band; but better still, by making the felly band smaller than it should be, so that the riveting or welding of the 120 spokes can be easily accomplished and by afterward stretching or expanding the felly band, which act tensions the wheel as a whole, the stretching being carried to the point necessary to give the peripheral rim or 125 band its correct circumferential measurement.

It is thought from this detailed description that the objects, purposes and advantages of my invention will be at once appar- 130

ent to those skilled in the vehicle wheel art, but inasmuch as this disclosure will readily suggest to others structures and methods whereby the substantial objects and purposes 5 of my invention will be attained, I do not wish to be limited to the specific construction herein shown and described, or to the precise steps and sequence referred to in the method of manufacturing the wheel, except 10 only as may be necessary by limitations in the hereunto appended claim.

I claim:-

The herein described method of making sheet metal wheels that consists in stamping from sheet metal a blank comprising a

solid middle portion and spokes extending from opposite edges thereof, then rolling the blank to cylindrical form and securing it in that condition, then swaging or expanding the ends of the solid middle portion and thus 20 causing the spoke portions to project radially therefrom, then securing the spoke ends to a peripheral metal member and finally stretching or expanding said member to a predetermined circumferential dimension, 25 thereby tensioning the wheel as a whole.

In testimony whereof I have hereunto set my hand this 7th day of May, 1918.

JOSEPH A. ANGLADA.
